FIRE PROTECTION APPARATUS

William Richter, Miami, and Peter Fray, Tampa,
Fla.

Application May 14, 1932, Serial No. 611,406

5 Claims. (Cl. 169—14)

Our invention relates to fire protection apparatus, and particularly to an apparatus of this character intended and adapted for installation and use in buildings, factories, garages, storage warehouses, aeroplane hangars, and on oil tank farms, and in other connections where a plurality of machines or units, or large areas, are to be protected.

An object of this invention is to provide an apparatus that can be readily and cheaply installed and maintained, and which is so constructed that water, chemical solution, or a mixture of the two in any desired proportion, can be supplied to and sprayed over any particular unit or area.

Another object is to so construct the apparatus and the controls therefor that all parts and portions are under complete supervision at all times from a central point to allow operation of different portions of the apparatus to spray water, chemical solution, or a mixture of the two in any desired proportion; as for example, an extinguishing chemical solution upon a burning oil tank, and plain water upon adjacent tanks for cooling the same to minimize the danger of overheating from proximity to the blaze to thus cause ignition or explosion of the adjacent tank, or its contents.

A further object is to provide an apparatus in which the supply of all liquids and solution is through the same distributing and spraying system, thus allowing most efficient installation at a minimum cost, and at the same time full and complete manual control parts are included to permit the user to operate the apparatus to secure most efficient results for each particular conflagration or other conditions.

Still another object is to provide an apparatus of this character including means for preventing the inoperativeness of the liquid diffusing or spraying system from the accumulation of frost, ice or other foreign matter or coatings at the outlets from which the liquid is sprayed, thus making the apparatus especially efficient for use in cold climates.

With the above and other objects in view, which will be apparent to those skilled in the art, our invention includes certain novel features of construction and combinations of parts which will be hereinafter set forth in connection with the drawings and then pointed out in the claims.

In the drawings:

Fig. 1 is a view in plan showing one form of our apparatus as applied for use with oil tanks or the like;

Fig. 2 is a view in longitudinal vertical section through a housing building and surroundings showing the apparatus in side elevation;

Fig. 3 is a fragmentary plan view illustrating particular adaptation of the parts in Fig. 1 for aeroplane protection;

Fig. 4 is a fragmentary vertical longitudinal sectional view showing the operating parts of Fig. 3 in side elevation;

Fig. 5 is a fragmentary view in side elevation of a section of conducting pipe illustrating a spray outlet; and

Fig. 6 is a transverse sectional view through the disclosure in Fig. 5 substantially on line 6—6.

As the parts are shown in Figs. 1 and 2 adaptation of the invention to protect a plurality of oil tanks, or other containers, as for instance on a tank farm, is illustrated and with this adaptation individual liquid spraying or diffusing installations are made for each particular tank, or other unit, and the operating mechanism and all controls are grouped at a central power and control station. With this plant and layout the control station is sufficiently separated from the tanks or other units to be unaffected by a fire or other disturbance at one or several of the units, and at the same time the plant can be set in operation and controls can be manipulated so that liquid can be sprayed upon and around any particular tank or unit for extinguishing flames, and a protective liquid, as water, can be sprayed at adjacent tanks or units to prevent ignition, explosion, scorching or other damage of the adjacent units from proximity to the conflagration.

A power station is diagrammatically illustrated at 1, and a water pump 2 suitably mounted therein is connected with a water main 3 or other suitable source of water supply, this pump 2 discharging to a water manifold 4 which can be extended to any desired length for the particular installation.

A chemical pump 5 suitably mounted in the central station has its intake 6 connected with a chemical storage tank 7, and the outlet 8 of this chemical pump leads to a chemical manifold 9, preferably located adjacent to and substantially coextensive with the water manifold 4.

An electric motor 10, or other suitable power unit, is directly connected to drive the water pump 2 and has a belted connection 11 with a pulley 12 on the shaft of the chemical pump 5. A manually controlled clutch 13 is preferably provided to cut in and cut out the chemical pump 5.

Where an electric motor is used as the power unit, current can be supplied from any suitable source and a switch 14, or other suitable control for the motor circuit, will be provided.

5 A valve 15 is preferably provided in the chemical supply pipe 6 to control the supply of chemical from storage tank 7, and it is also perhaps desirable that a valve or other control means be provided for the water supply pipe 3, such control means for water supply pipes being old and well known and therefore not here illustrated in detail.

10 A plurality of liquid conducting pipes 16 are connected with the water manifold 4 to extend laterally therefrom, and these liquid conducting pipes are extended to any desired length and to terminate at the particular unit or adjacent to the particular area to be protected. In the present instance we have shown two oil tanks T, or 15 like containers, and the liquid spraying or diffusing system in this instance includes a ring pipe 17 and cross pipes 18, all connected to be in direct communication with the liquid conducting pipe 16. These pipes 17 and 18 have spraying 20 openings 19 formed therethrough, one illustration being shown in Figs. 5 and 6, and shields or hoods 20 are preferably located over the spray openings to protect the same against the accumulation of ice, frost, dirt, or other foreign 25 matter that might clog the spray opening 19 or otherwise interfere with the free and efficient spraying of liquid therethrough.

30 In the present instance, we have shown the chemical manifold 9 located on a lower level than water manifold 4, and chemical conducting pipes 35 21 are connected to extend laterally from this manifold 9 to connect with the main liquid conducting pipes 16 on their undersides and at points slightly spaced from the water manifold 4. With 40 this connection and arrangement of the parts chemicals flow through the chemical supply pipes 21 and discharge into the liquid conducting pipe 16 and will be carried along and mixed with water flowing under pressure from water manifold 4 45 through the conducting pipe 16, and in consequence a solution of water and chemical will be supplied to discharge through spray openings or nozzles 19.

50 Cut-off and regulating valves 22 are provided in each of the liquid conducting pipes 16 closely adjacent to the water manifold 4 so as to not affect the connection of the chemical supply pipes with the conducting pipes 16, and similar valves 55 23 are mounted in each of the chemical supply pipes 21 to control the supply of chemical through these pipes to the conducting pipe 16.

60 As illustrated in Figs. 3 and 4, the liquid conducting pipe 16 leads to a liquid spraying device intended primarily for use in an aeroplane hangar, to be installed above each particular and individual machine berth or space, and in this adaptation the pipes 24 and 25 are disposed to extend substantially longitudinally throughout the length of the fuselage and transversely throughout the wing spread, liquid spraying openings or nozzles being provided at suitable intervals along the lengths of these pipes to allow the spraying and diffusion of fire extinguishing or protecting liquids over and upon substantially all parts of the aeroplane.

65 In the use of our improved apparatus the individual tanks or protective units or areas can be numbered or otherwise designated and the liquid conducting pipe 16 and associated control valves

will be similarly marked or designated in the central station. When a fire or other dangerous condition is noted at any particular unit or in any particular area or location, an operator can throw the switch 14 to initiate operation of the power unit and water pump 2 and clutch controlled chemical pump 5 can be operated. If water only is to be sprayed in a particular area, the pump 5 need not be operated, or the chemical supply can be cut off through valve 15, or through the individual valves 23. Where water alone is to be used the valve 22 in the conducting pipe 16 leading to the affected area is opened and the pump 2 then forces water under pressure from manifold 4 to be discharged through the spray openings or nozzles 19. If desired, chemical alone can be supplied through one or several of the liquid conducting pipes 16 by closing valves 22, throwing in clutch 13, opening valve 15 from the chemical supply tank, and then opening the valve 23 in the chemical supply pipe 21 leading to the desired liquid conducting pipe 16. Where liquid is desired to extinguish an oil fire, chemical will probably be supplied, as indicated at the lower tank in Fig. 1, and if adjacent tanks be sufficiently separated to avoid the danger of overheating to ignite or explode the contents, it may not be necessary to supply any liquid through the conducting pipe to the adjacent tank, as shown in Fig. 1; however, it will be possible to supply chemical through the liquid conducting pipe to this adjacent tank, to supply a mixture of water and chemical in any desired proportions by manipulating the associated valves 22 and 23, or to supply water only for cooling purposes by opening only the valve 22 to the connected liquid conducting pipe, while leaving the valve 23 in the associated chemical conducting pipe 21 closed.

70 The manipulation of the valves can of course be varied to suit the particular installation and the particular requirements of use; and, the arrangement of sprinkler or spraying pipes can be varied from the two forms illustrated, to adapt the structure and apparatus to spray liquid over any particular size and shape of area or over a unit or object of any particular and peculiar form.

75 While we have herein shown and described only certain specific embodiments of our invention and have illustrated and suggested only certain possible modifications, it will be appreciated that many changes in the form, construction, arrangement and installation of the parts can be made to suit various conditions of use and operation, without departing from the spirit and scope of our invention.

We claim:

1. A fire protection apparatus comprising a plurality of liquid conducting pipes leading from a central location to points where liquid is to be used, a source of water supply, pump means at the central location to supply water under pressure from the source of water supply, a source of chemical supply, pump means also at the central location to supply chemical under pressure, a connection from said water pump to each of said liquid conducting pipes, a control valve in each said water connection, a connection from the chemical supply to each of said liquid conducting pipes, and flow control means in each of said last named connections.

2. A fire protection apparatus comprising means to store chemical solution, a plurality of liquid conducting pipes, spray means associated with said conducting pipes, a source of water supply, a water supply connection to each of said

conducting pipes, connections from said chemical storage means to each of the conducting pipes beyond the water supply connections, individually operable valves located in each of the water supply connections and each of the chemical connections to each of said liquid conducting pipes; and means to place the water and chemical solution as supplied under pressure.

3. A fire protection apparatus comprising means to store chemical solution, a plurality of liquid conducting pipes, a source of water supply, liquid distributing means associated with said conducting pipes, a water supply connection from said source to each of said conducting pipes, connections from said chemical storage means to each of the conducting pipes beyond the water supply connection therewith, and means to control the supply of chemical and water through each of said connections.

20 4. A fire protection apparatus comprising a plurality of liquid conducting pipes leading from a central location and terminating with their discharges at spaced points; liquid distributing means at said discharge ends, a water supply manifold at the central location, a source of water supply connected with said water manifold, a chemical supply manifold also at the central location, a source of chemical supply connected with said chemical supply manifold, connections

from said water manifold to each of said liquid conducting pipes, connections from said chemical supply manifold to each of the conducting pipes at points beyond the water connections, and individually controllable valves in each of said water and chemical supply connections adjacent to the manifolds.

5 5. A fire protection apparatus comprising a plurality of liquid conducting pipes leading from a central location and terminating with their discharges at spaced points, liquid distributing means at said discharge ends, a water supply manifold at the central location, a source of water supply connected with said water manifold, a chemical supply manifold also at the central location, a source of chemical supply connected with the chemical supply manifold, connections from said water manifold to each of said liquid conducting pipes, connections from said chemical supply manifold to each of the conducting pipes 10 at points beyond the water connections, individually controllable valves in each of said water and chemical supply connections adjacent to the manifolds, means to supply water to said water manifold under pressure, and controllable means 15 to supply chemical to said chemical manifold under pressure.
